CHARLES TITUS, OF UNION, MAINE.

Letters Patent No. 80,082, dated July 14, 1868.

IMPROVEMENT IN DRESSING BARRELS.

The Schedule referred to in these Letters Patent and making part of the same.

TO ALL PERSONS TO WHOM THESE PRESENTS MAY COME:

Be it known that I, CHARLES TITUS, of Union, in the county of Knox, and State of Maine, have invented a new and useful Machine for Dressing and Crozing the Staves of a Barrel; and I do hereby declare the same to be fully described in the following specification, and represented in the accompanying drawings, of which—

Figure 1 is a top view,

Figure 2, a front elevation, and

Figure 3 a longitudinal section of it.

Machines commonly employed for crozing and chamfering a stave at either or both of its ends, are generally designed to operate on a single stave at a time, whereas my machine is intended to chamfer and croze at one and the same time an entire set of staves when set up and hooped for being made into a barrel.

In the drawings, A denotes a cutter-head, whose upper part, *a*, has the form of a conic frustum, such head being fixed on the upper end of a vertical shaft, B, supported by and so as to be capable of being revolved within a frame, C, and by a belt going around a pulley, *c*, fixed on such shaft.

The lower part, *b*, of the cutter-head is a circular disk, having a diameter somewhat larger than that of the base of the part *a*, and containing one or more cutters, *d*, arranged within it, and so as to project above its upper surface. The two parts *a* and *b* may be in one piece of metal.

An annulus or ring, D, supported by posts E E of the frame C, surrounds the part *a* concentrically, and is for centralizing the collection of staves, and properly presenting and guiding it to the cutters of the cutter-head.

There are arranged on the periphery of the part *a* of the cutter-head two or any other suitable number of cutters, *e e*, whose office is to chamfer the set of staves, each cutter being placed and fixed in a suitable throat made in the cutter-head.

Arranged in the cutter-head, and so applied thereto as to be capable of being moved radially therein, are two carriages or sliders, F G, one of which supports a hollowing-cutter, *f*, and the other a crozing-cutter, *g*.

Figure 4 is a diagram, showing an edge view of the end portion of a stave as formed by my said machine.

The cutters *e e* produce the chamfer *i l* of the stave. The cutter *f* forms the groove *k l*, and the cutter *g* makes the croze *m*.

Each of the sliders F G has applied to it one of two bent levers, *n n'*, whose fulcrums are supported by arms *o*, projecting down from the cutter-head.

The shorter arms of the two levers *n n'* are jointed to two collars or tubes, *p q*, arranged concentrically on the shaft B, and applied thereto so as to be capable of being moved vertically therein. Each of the said collars has one of two treadles or levers, *r s*, applied to it for moving it upward, a spring *t*, to each treadle serving to effect the downward movement of the collar. By an attendant putting his foot on either of the treadles and depressing it, he will cause the cutter-carriage F or G, connected therewith, to be advanced so as to bring its cutter into action while the cutter-head may be in revolution. The shaft B revolves with the collars, which revolve in their treadles.

After the staves have been set up and hooped, the series is to be placed endwise within the guide-ring D, and upon the bevelled edge of the cutter-head. Such head being supposed to be in revolution, its chamfering-cutters will chamfer all the staves preparatory to their being grooved and crozed. After the chamfering of the staves may have been carried on so that they may meet the edge-cutters of the lower part of the head, such edge-cutters will reduce or dress off the ends of the staves. After this, the grooving-cutter should be projected so as to cut into and groove the staves, and, finally, the crozing-cutter should be advanced so as to form the croze in them.

I make no claim to any thing, combination, or arrangement as described in either of the United States patents, Nos. 11,894, 41,248, and 41,249, the cutter-carriers of my machine being operated by treadles, collars, and bent levers, arranged in a peculiar manner with respect to each other and with the cutter-head and its shaft, the same rendering the machine simple in construction, and easily operated by an attendant, as circumstances may require.

I claim the arrangement and combination of the separate levers or treadles *r s*, the collars *p q*, and bent levers *n n'*, with one another and the shaft B, the cutter-head A, and the cutter-carrier E G, such head and carriers being provided with cutting and a guide-ring, D, as set forth.

CHARLES TITUS.
